METHOD AND SYSTEM FOR HIGH
VELOCITY AIR CONTROL

William J. Caldwell, Bronxville, N. Y., assignor to
J. H. McCormick & Co., Williamsport, Pa., a
corporation of Pennsylvania

Application September 10, 1931, Serial No. 562,077

5 Claims. (Cl. 98—40)

This invention relates to the control of air, conditioned or otherwise, when supplied to a space for ventilating, cooling and heating purposes at high velocity, that is, at lineal speeds upwards of 2500 feet per minute.

It is desirable in most cases, that air supplied to any living space be conditioned with respect to temperature and humidity so as to provide the greatest comfort for the people therein. Heretofore, many systems have been devised for heating, cooling, and ventilation but with an air supply moving through grills or louvres at speeds of 600 to 1200 feet per minute, resulting in the necessity for large ducts, large grills or a large number of small grills and also the necessity for some sort of exhaust system in order to direct the air movement.

Other systems have been devised in which dependence is placed on secondary circulation amounting to three or four times the volume of the primary circulation, an insufficient amount of new air being introduced into the space, but that small amount stirring up the stale air already there.

An object of the present invention is to provide an improved system or method for heating, cooling, and ventilating living spaces by controlled, high velocity air movement without drafts and without refrigeration and with a plentiful supply of outside air and a minimum of recirculated air or none at all, and without the necessity of providing an exhaust system to control the air movement.

A further object of this invention is the creation within a space of sufficient positive air pressure to prevent the infiltration of unconditioned air through cracks or openings, maintaining at all times an outward flow of air from the space and thus preventing the entering of dirt and dust from without through doors and windows.

Still another object of this invention is to maintain within the space an air movement above the dew point velocity of the air introduced, that is, above the velocity at which that air will deposit moisture or feel "clammy". It is well known, for example, that evaporation is hastened by air movement and even on a humid day one is comfortable in a breeze, and wet clothes on a wash line will dry on a humid day quickly only in a breeze. This is owing to, among other things, the fact that moving air if moving rapidly enough, say 200 to 300 feet per minute, will pick up and maintain more moisture than still air and will give to the body the effect of a drop in humidity because of rapid replacement of the adjacent

more or less saturated layer of air by new unsaturated air. Moving air will give the effect of a lower temperature than still air, if the body is moist. This action is true of inanimate bodies such as tinware and mirrors, as well as the living body. By "dew point velocity" I mean that velocity of air which moving over a mirrored surface will remove moisture which clouds the mirror when the air is still under the same conditions of temperature and humidity.

An object of my invention is to take advantage of the effective temperature and humidity drops due to moving air above the dew point velocity, without objectionable drafts, and maintain comfortable conditions within a space by air movement which would be considered excessive by conventional standards based on low velocity air supply through grills.

Another object of my invention is to control the direction and distribution of air within a space without the use of ducts or conduits within the space.

With the foregoing and other objects in view, as will be apparent as the description proceeds, my invention resides in the combination and arrangement of parts and the adaptation of known laws to produce a new result, as described in this specification and particularly pointed out in the appended claims. I intend no limitations other than those of the claims.

The method herein described and claimed is not limited to any particular devices for its successful accomplishment and it is desired that the present disclosure be considered as illustrative and not in any limiting sense.

In order to give a full, clear, and concise description of my method and system of air control, reference is made to the accompanying drawings which illustrate diagrammatically the various steps involved in an embodiment of my invention.

Fig. 1 represents diagrammatically a complete installation of an air control system embodying my invention.

Fig. 2 is a diagrammatic representation in detail of the control system shown in Fig. 1.

Fig. 3 illustrates the cooperative arrangement of multiple nozzles.

Fig. 4 illustrates in front view the assembly of three nozzles to the discharge elbows and duct.

Fig. 5 is a side view, partly torn away to illustrate the ball joint connection between nozzle and elbow.

The same reference characters refer to similar parts in all views.

Turning now to Fig. 1, a high velocity blower or fan 1 discharges through a supply duct 14, square to round transformations 15', elbows 15, to ball jointed cylindrical nozzles 16 provided 5 internally with rifling or other means such as ribs adapted to impart a whirling motion to the air streams issuing from said nozzles shown in front elevation in Figs. 3 and 4. By reason of the ball joint between nozzle 16 and elbow 15 the 10 nozzle is directionally adjustable. These nozzles 16 discharge high velocity, whirling air streams into the conditioned space 20. A by-pass 24 operated by a reversing damper motor 4 is 15 remotely controlled as by a switch 25' or double button 25' (Fig. 2) serves to permit adjustment of the air supply through duct 14.

Fan 1 may be located in an enclosed plenum chamber 30, and is actuated by a motor 2, the 20 starter box 27 being located conveniently there-to, with remote stopping and starting control as at 26. With the type of blower preferred, an across-the-line starter is used.

Air is supplied to plenum chamber 30 by the 25 fan suction through a vortex air washer 6, the discharge from said washer being indicated as at 5 and intake to washer 6 being tangential as at 7, a suitable baffling 8 preventing other intake of air to chamber 30.

The fresh or outside air supply is through a 30 downdraft intake 11, avoiding the heat of roof 13. A drain 12 is preferably located as shown. Intake louvres 23 set in the plenum chamber wall are actuated by a damper motor 19 controlled by a thermostat 22 in mixing space 10 as 35 will be later explained. The air entering through intake louvres 23 to mixing space 10 may be drawn through the heat units 9 to which steam is supplied through a motor actuated steam supply valve 29 controlled by a thermostat 28 located in 40 the conditioned space 20. In summer time or mild weather, the vertically sliding door 3, balanced by a counterweight 36, may be slid up over the heat unit 9, permitting air to flow directly from space 10 to the air washer intake 7.

45 By reason of the intake of a positive quantity of outside air and the static head at which air is forced into the space, a definitely positive pressure may be maintained in the space, whereby outward pressure against infiltration of air may 50 be had at window cracks and similar places.

A recirculation duct may be provided as at 17 having a louvred discharge as at 18 into the mixing chamber 10, the louvres 18 being connected to the lever arm of damper motor 19 in such manner as to close when louvres 23 open, and vice versa.

Damper motors 4 and 19 and motor operated valve 29, controlled respectively by manually operated switch 25, thermostat 22 and thermostat 60 28 (Fig. 2) are supplied with electric power through distribution wires 35 from a power box 32, preferably containing a step down transformer 31, and suitable protective and reset device 33 on the power main 34.

65 In operation air velocities as high as 9000 feet per minute from nozzles 16 may be used without objectionable drafts, the air discharged from the rifled nozzles 16, 16, whirling in a constantly expanding stream which takes on substantially a cone shape or vortex with a constantly decreasing forward speed so that as it expands into the occupied space it is moving just above the dew point velocity, preferably about 300 feet per minute. The entire air of the treated space is in 70 motion resembling a sort of "boiling" action. Be-

cause of this motion there is an effective drop in humidity and temperature giving a sense of comfort to the occupants of the space but without drafts from any given direction.

As indicated in Fig. 3 the discharge is from 5 a plurality of closely adjacent nozzles, the issuing air streams having opposite whirling or rotating direction as represented by the arrows, wherefore the nearby or adjoining portions of the streams have the same tangential direction 10 resulting in an effectual "gearing" together of said streams. This opposite stream rotation is accomplished by providing the adjacent nozzles with oppositely directed rifling and the resulting "geared" condition of the streams causes said 15 streams to have a cooperating directional rotation assisting in the forward axial movement thereof. In other words if the discharged whirling air streams were all rotating in the same direction, the nearby or adjoining portions would 20 have opposing tangential motion resulting in a "bucking" or frictional interference with each other materially reducing the energy of the forward axial propulsion, and causing undesired opposing turbulence in the locality of the noz- 25 zles, and creating some degree of noise. This undesired diminution of energy is overcome by the "gearing together" of the air streams and therefore the opposite rotation may be truly said to assist in the forward axial movement of said 30 streams.

By reason of the ball joint of the rifled nozzles 16, 16, they may be fanned out or tilted up and down to change the linear or axial direction of the discharged air streams in order to prop- 35 erly distribute the air supply and avoid columns, pillars, fixtures, and the like. In winter, the air throw may be over the lights, utilizing the heat of the lights throughout the room. In summer weather, the nozzles may be tilted down. 40

Stopping and starting the blower is done by a control 26. The amount of air is adjustable by control 25. Automatic regulation of steam supply to the heat unit 9 is accomplished by thermostat 28 in the treated space. The ther- 45 mostat 22 in mixing chamber 10 is set to main- 50 tain a certain temperature in mixing chamber 10 above the freezing point and below room tem- 55 perature of space 20. This temperature is de- 60 termined both by the outside temperature and the temperature of the recirculated air drawn through duct 17 from the space 20. If the with- 65 drawn air is too warm, thus raising the tem- 70 perature of space 10, damper motor 19 opens the intake louvres 23 wider and closes the re- 75 cirulation louvres 18 more. If the space 20 gets cold, due to lack of fire, thus lowering the tem- 80 perature of space 10, intake louvres 23 are closed and recirculation louvres 18 opened wider. If 85 there is a sudden drop in outside temperature without increase in furnace firing, thus lower- 90 ing the temperature of space 10, louvres 23 will close and louvres 18 will open. The underlying 95 action of damper motor 19 is determined, not by the ventilation requirements of space 20 but by the actual heat units supplied to space 20 above the loss of heat from the room from any cause. It is a supplementary action to that of thermo- 100 stat 28 which regulates the steam supply to heat unit 9. 70

With thermostat 28 set at 72° F., for exam- 105 ple, if the space 20 falls below 72° the steam valve 29 opens wide and steam is called for. It may not be available in sufficient quantity to heat the space 20 either because of inadequate 75

firing, open doors, poor coal, or other reason. In this case the room temperature will not rise and chamber 10 will fall in temperature because the air passing through duct 17 is colder. Thermostat 22 thereupon cuts down the fresh air to the point where the heat units available to space 20 are sufficient to heat that space, in spite of the loss of heat from the space.

On the other hand, if space 20 rises in temperature above the setting of thermostat 28, the steam valve 29 will close and cut off the steam. Space 20 may still remain above the setting of thermostat 28 because of the heat from the lights, for example, or from overcrowding, or because of cooking stoves, or any other reason. Then chamber 10 will rise in temperature and more outside air will be taken into space 20 until that space is lowered to the setting of thermostat 28.

Moreover, it is apparent that the adjustment of louvres 23 and 18 changes the amount of air supplied to plenum chamber 30 and to space 20. If louvres 18 are closed, the resistance of the recirculation duct is cut off and a maximum amount of air is handled, directly from intake louvres 23. If, on the other hand, louvres 23 are closed and louvres 18 wide open, a minimum quantity of air will be handled through the resistance of the recirculation duct and opening.

Preferably recirculation duct 17, when used, is located adjacent the air supply nozzles 16 and at the top of space 20, giving rise to an air movement within space 20 not unlike a whirling stocking drawn constantly inside out.

What I claim as new is:

1. The method for high velocity air distribution which comprises providing suitably conditioned air for supply to a space and discharging this conditioned air directly into the space well above the occupied section in a plurality of adjacent cooperating whirling and constantly ex-

panding streams having opposite rotating motion.

2. The method for high velocity air distribution which comprises providing suitably conditioned air for supply to a space, discharging this conditioned air directly into the space well above the occupied section in a plurality of adjacent whirling and constantly expanding streams having opposite rotating motion, and varying at will the axial directional flow of each stream.

3. In a system for air distribution means for suitably conditioning air for supply to a space; and means for discharging the conditioned air into said space in a plurality of adjacent cooperating streams having opposite rotating motion, said discharge means comprising a plurality of nozzles each provided internally with rifling, the rifling of two adjacent nozzles being oppositely directed.

4. In a system for air distribution, means for suitably conditioning air for supply to a space; and means for discharging the conditioned air into said space in a plurality of adjacent cooperating streams having opposite rotating motion, said discharge means comprising a plurality of nozzles each provided internally with rifling, the rifling of two adjacent nozzles being oppositely directed, said nozzles mounted closely side by side and normally directed to cause the discharged air streams to have substantially parallel axial directions.

5. A structure for conditioning the air of an occupied space, said structure comprising an enclosure provided with an opening for admitting air from said space to be recirculated; an inlet for fresh air adjacent said opening; means for suitably conditioning the fresh air and the air to be recirculated; and means to discharge the conditioned air including a plurality of closely adjacent nozzles adapted to create cooperating air streams having opposite rotating motion.

WILLIAM J. CALDWELL.
